AIR DRAFT CONTROL APPLIANCE

Cuthbert Vincent, Omaha, Nebr.

Application January 28, 1939, Serial No. 253,299

1 Claim. (Cl. 277—60)

This invention relates to an air draft control appliance for preventing waste of fuel, and is specifically designed for use in connection with oil burners generally used on furnaces, said oil burners being of various kinds or types, but usually being equipped with a motor-driven fan as a feature intended to assist combustion of the vaporized or atomized oil.

Since chimneys vary in proportions and heights the degree of draft for furnaces, comparatively, will not be uniform, and it often happens that an excess of chimney draft carries away unconsumed gases.

Also there is often a loss of fuel by action of the fan in instances when the flow of oil to the burner is not uniform, or in instances when there is a lack of uniformity in the quality of oil supply. Also there may be a loss of fuel when the action of the motor-driven fan is not uniform as to speed.

It has been observed that, according to the construction of oil burners now in general use, no attempt has been made to provide means which operate automatically to prevent an excess movement of air through the oil burner and furnace when there is a change in speed, or when the fan ceases rotation. One of the objects of the present invention is to provide an air draft appliance which will accomplish these purposes so that unconsumed gases will not be lost.

Another object of the invention is to provide an automatic appliance which normally will maintain the air intake port of the oil burner in closed condition at all times except when the fan is in action, and which will automatically open when the fan is in operation.

Other objects of the invention will appear in a complete and clear description hereinafter set forth.

The invention consists of the new and useful construction, combination and arrangement of parts as described herein and claimed, and as illustrated in the accompanying drawing, it being understood that changes may be made in form, size, proportions and minor details, said changes being within the scope of the invention as claimed.

In the drawing,

Fig. 1 is a view in side elevation, partly broken, showing the air draft control appliance.

Fig. 2 is a plan view of the appliance, the top portion of the sleeve or cylindrical housing being broken away to show the location of a pair of hingeably mounted wings.

Fig. 3 is a sectional view showing a wing pro-

vided with an adjustably mounted weight-member.

Fig. 4 is a front view of the appliance, the wings being shown in closed position, and Fig. 5 is a rear view of the same.

Fig. 6 is a broken away side view in longitudinal section showing a part of an oil burner with the appliance mounted thereon.

Referring now to the drawing for a more particular description, the invention is shown and described in connection with a part of the housing 7 of an oil burner provided with a fan 8 in suitable bearings for rotation for moving air in the direction indicated by the arrow shown in Fig. 6 to a furnace (not shown).

Since the construction and operation of oil burners used for heating buildings are well known it is not considered necessary to show means for rotating the fan, or to show pipes for conducting oil.

The invention consists, in part, of a cylindrical housing or sleeve 9 having its free end formed with a downward and inward inclination as indicated at 10.

Numerals 12 indicate a pair of semicircular wings hingeably mounted at their rectilinear edges upon a pintle 11 which is disposed parallel with the inclined end 10 of the housing or sleeve 9, this inclination for the pintle 11 operating as an aid for an automatic movement of the wings 30 to closed position.

Numerals 13 indicate apertured ears, and by means of keepers 14, the housing or sleeve 9 is secured to the casing or housing 7 of the oil burner, the air intake for said member 9 being 35 in register with the air intake of the oil burner.

In operation, rotation of the fan will cause the wings to swing inwardly to the position shown in dotted lines in Fig. 2. In order that this inward swinging movement will not cause the wings to be disposed relatively parallel, a spacing-block 15 (Fig. 6) carried by the top of the sleeve 9 is disposed rearwardly of the pintle 11 midway between the wings.

When the wings, by action of the fan, have 45 moved inwardly to the position shown by said dotted lines in Fig. 2, it is obvious that this change in inclination may tend to prevent a reverse swinging movement of the wings, by action of gravity, to closed position when the fan ceases 50 its rotation, and therefore I have provided a pair of weight-members 16 and have mounted them on the inner sides of the wings as best shown in Fig. 5 of the drawing, and since these weights are disposed remote from the axis of movement of 55

said wings, the latter will quickly respond to the action of gravity for movements to closed position.

Numerals 17 indicate a pair of stop-members which are carried by the sleeve or housing 9 and 5 which are disposed outwardly of the wings to limit their outward swinging movements.

Since it is not a desirable feature, when the wings are in closed position, to completely prevent a draft of air through a furnace, the wings 10 are of such proportions that passageways 18 (Figs. 4, 5) will permit a limited intake of air at all times.

It will be understood that the axis of movement for the swinging movements of the wings 15 should be disposed in a vertical plane at a suitable inclination relative to a horizontal plane so that their swinging movements may be coincident and uniform.

In order that the wings may more readily move 20 to closed position by action of gravity, the weight-members 16 may be adjusted horizontally, and

may be disposed nearer to the outer edges of the wings, horizontal slots 19 being formed in the wings (Fig. 4), and by means of thumb-screws 20 the weight-members may be secured at selected distances from the axis of movement of said wings. 5

I claim as my invention:

The herein described means for air draft control comprising, in combination with a horizontal air draft pipe provided interiorly with an upwardly and outwardly inclined pintle, a pair of wings each provided with a horizontal slot and swingably mounted on the pintle, a pair of keepers each engaging in a slot of a wing and provided with a weight-member arranged to be secured to a wing at selected distances from said pintle to control the degree of swinging movement thereof for a control of air movements through said draft pipe. 15
